(74) Attorney, Agent, or Firm — SNR Denton US LLP;
Brian R. McGinley(57) **CLAIM**

The ornamental design for a ring, as shown and described.

DESCRIPTION

FIG. 1 is an enlarged top view of a first embodiment of the ring;

FIG. 2 is an enlarged bottom view of the ring illustrated in FIG. 1;

FIG. 3 is a right elevational view of the ring illustrated in FIG. 1;

FIG. 4 is a left elevational view of the ring illustrated in FIG. 1;

FIG. 5 is a front view of the ring illustrated in FIG. 1;

FIG. 6 is a rear view of the ring illustrated in FIG. 1;

FIG. 7 is a perspective view of the ring illustrated in FIG. 1;

FIG. 8 is an enlarged top view of a second embodiment of the ring;

FIG. 9 is an enlarged bottom view of the ring illustrated in FIG. 8;

FIG. 10 is a right elevational view of the ring illustrated in FIG. 8;

FIG. 11 is a left elevational view of the ring illustrated in FIG. 8;

FIG. 12 is a front view of the ring illustrated in FIG. 8;

FIG. 13 is a rear view of the ring illustrated in FIG. 8; and,

FIG. 14 is a perspective view of the ring illustrated in FIG. 8.
